UNITED STATES PATENT OFFICE.

WILLIAM T. S. BROWN, OF EAST POINT, GEORGIA.

FASTENER FOR CONTAINERS.

Application filed December 2, 1925. Serial No. 72,800.

This invention relates generally to boxes, crates, and other containers, and more particularly to a fastener for holding parts of the container together both in the assembled 5 and package form.

It is an object of the invention to provide a fastener of improved form that not only may be used instead of that shown by Fig. 8 of my United States Patent No. 1,468,340 10 for holding together elements of a box or crate assembled, for example, as disclosed by Figs. 1, 5, and 6 and in a package of disassembled parts as shown, for example, by Fig. 7 of that patent, but also otherwise in 15 a container, whereby there is afforded a device of a single type that is capable of meeting various requirements in structures of this general class.

When considered with the description 20 herein, the characteristics of the invention are apparent from the accompanying drawing, forming part hereof, wherein an embodiment of the invention and its manner of use are disclosed, for purposes of illustration.

Although the disclosures herein exemplify what now is considered to be a preferable embodiment of the invention, it is to be understood that it is not the intention to be 30 limited necessarily thereto in interpretation of the claims, as modifications and adaptations within the limits of the claims can be made without departing from the nature of the invention.

Like reference characters refer to corresponding parts in the views of the drawing, of which—

Fig. 1 is a view of a box or crate having 40 its parts held together by fasteners formed in accordance with this invention;

Fig. 2 is a view of the parts in package form;

Fig. 3 is a fragmentary view of a box illustrating another way in which the fastener may be used;

Fig. 4 is a similar view illustrating still another use of the fastener;

Fig. 5 is a view of the fastener;

Fig. 6 is a view of the nut thereof.

Having more particular reference to the drawing, A designates end members having marginal battens A', B side members having battens B' near their ends, and C top and bottom members, of a box or crate. 55 When these members are assembled to

constitute a container, the ends of the top, bottom, and side members extend inside of the battens A' of the end members, and those battens abut the battens B' of the side members. The members A, B, and C preferably are rectangular in plan, and members that are positioned oppositely in the container are substantially identical, in order that they may be used interchangeably. 60

The side battens B' and the walls of the end members and the battens A' thereof that abut the battens B' are formed with holes or passages D, which are positioned so that those of abutting or opposite battens 70 are aligned when the parts are assembled as a container.

These elements, formed as described, may be held together, both as a container or as a package of knocked-down parts, by the 75 fasteners disclosed by my patent hereinbefore referred to. However, in order to afford a fastener that will answer that purpose as well and also be more suitable for employment in other ways in a container, 80 I have provided the fastener disclosed herein.

That fastener comprises a member having a head 7 and a threaded shank 8 of the general form of a machine-screw, and a nut 9 85 cooperable therewith. The nut is of plate-like form, somewhat elongated, and preferably rectangular in plan. It has a threaded opening 10 of a size to take and to cooperate with the threaded shank 8 and 90 another and larger opening 11 through which a shank of the size to engage in the opening 10 may move freely.

When fasteners of this form are used to hold together parts assembled as a container, 95 the shanks are disposed in the aligned passages D with the heads on the outside of the end walls and the nuts bearing against the opposite sides of the battens of the side members. The elongated nuts are prevented 100 from turning while the shanks are being turned thereinto or therefrom by bearing against the walls of the side members.

When knocked down parts of the container are assembled in package form, the top, bottom, and side members are located between the end members, and the openings through the latter members are approximately in alignment. A threaded shank of the fastener is passed inwardly through the opening 110

of each of the end members and through a larger opening of one of a pair of the nuts and turned into the threaded opening of the other nut, and the two threaded shanks 5 are turned and tightened to hold the parts of the package firmly together. As seen in Fig. 2, the nut having threaded engagement with one shank is beyond the nut having similar engagement with the other shank. 10 Thus the two nuts of the opposed shanks are lapped and hold the two shanks together and the container parts in package form.

The fastener of this invention not only 15 may be employed as exemplified by Figs. 1 and 2, but it also may be used otherwise to maintain parts of a box, crate, or other container together. For example, the plate-like nut may be set into a batten of one 20 wall of a container and the screw turned through an abutting batten of another wall and into the nut, as shown by Fig. 3; or the nut may be placed against a side of a batten and held thereon by a nail or other holding member driven through the non-threaded opening and the screw turned 25 through an abutting batten into the threaded opening of the nut, as shown by Fig. 4.

Having thus described my invention,

what I claim as new, and desire to secure 30 by Letters Patent, is—

1. A package of container parts having fastener-openings in its outer members, and fasteners comprising threaded shanks disposed inwardly through said openings and 35 nuts arranged in lapping pairs and each nut having a threaded opening and another opening through which one of said shanks is movable freely, each of said shanks extending first through the latter opening of one nut and into engagement with the threaded opening of the other.

2. A fastener comprising two threaded shanks arranged to be disposed in two oppositely-positioned parts for the purpose of 45 holding them together and having heads capable of bearing against the outside of said parts, and nuts arranged in lapping pairs, each nut having a threaded opening and another opening through which either 50 of said shanks is movable freely, and each of said shanks extending first through the latter opening of one nut and into engagement with the threaded opening of the other.

In testimony whereof I affix my signature. 55

WILLIAM T. S. BROWN.
